UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

INTERMITTENT THREAD-CUTTING TEMPLE.

Application filed January 9, 1925. Serial No. 1,499.

To all whom it may concern:

Be it known that I, ALONZO E. RHOADES, a citizen of the United States, and a resident of Hopedale, county of Worcester, State 5 of Massachusetts, have invented an Improvement in Intermittent Thread-Cutting Temples, of which the following description, in connection with the accompanying drawing, is a specification, like characters on the 10 drawing representing like parts.

This invention relates to improvements in intermittently operated temple thread cutters for looms of the automatic filling replenishing type.

15 The object of the invention is to provide a novel and simple temple thread cutter construction in which the thread cutting mechanism is operated for a predetermined period after the operation of the filling replenishing mechanism and then rendered inoperative until the next call for filling replenishment.

In usual types of temple thread cutters the reciprocating thread cutting member is 20 actuated upon each beat-up of the lay, whereas only such actuation is necessary as is required unerringly to sever the filling end which projects from the selvage edge of the web of cloth after transfer has been effected. Hence the cutting mechanism is subject to a large amount of unnecessary wear.

Various means have heretofore been provided for rendering the operation of the 25 parting mechanism intermittent so that it will act only for a short period after filling replenishment. Such mechanisms have usually been associated with the temple itself and are comparatively small and more or 30 less delicate in construction.

One of the objects of the present invention is to provide a more rugged construction which will stand up under the wear and shock of the loom and which will be supported wholly or mainly from the temple stand.

A further object of the invention is to 50 provide a detent pivotally mounted upon the temple stand adapted to engage the movable thread parting device and positively hold the parting device out of operative position during the normal running of the loom with means operable by the changing mechanism of the loom for releasing the thread cutting device and permitting it to be re-

stored to operative position and also with a bodily movable timing device operable to lock the detent in inoperative position for a predetermined period after call for transfer and with means intermittently actuated by a predetermined number of movements of the parting device to restore the detent to operative position.

A further object of the invention is to provide a longitudinally adjustable detent whereby the relation of the detent to the movable parting device may be accurately positioned.

Other objects and features of the invention will more fully appear from the following description and the accompanying drawings and will be particularly pointed out in the claims.

As the invention is adapted to be applied to loom constructions of usual types only so much of the loom is illustrated in the accompanying drawings as is necessary to show the association of the present invention therewith.

In the drawings:

Fig. 1 is a side elevation of a loom temple construction embodying the present invention showing the position of the mechanism and of the controller arm when the parting device is in operative position;

Fig. 2 is a similar view showing the position of the mechanism when the parting device is held in inoperative position during the normal operation of the loom;

Fig. 3 is a similar view showing the position of the parts of the mechanism immediately after call for transfer and before restoration of the changing mechanism to normal position;

Fig. 4 is an end elevation of the mechanism shown in Figs. 1, 2 and 3;

Fig. 5 is a detail cross sectional view on line 5—5 Fig. 1 showing the adjustable connection between the members of the extensible detent; and,

Fig. 6 is a detail view showing the reverse side of the ratchet of the timing device and illustrating in section the pawl which is carried by the parting device and the stud upon the detent located in operative position within the cam slot of the timing device which, when the timing device is rotated, serves to lock the detent in inoperative position.

The present invention comprises mecha-

- nism for controlling the action of the temple thread cutter adapted to be associated with the usual type of filling replenishing loom, such for example as the well known "Nor-
5 throp" type of loom. The parts of the loom which are illustrated herein comprise a breast beam 1 and a controller rod 2 through which the action of the filling replenishing mechanism, or other means for changing
10 the operation of the loom is initiated, and the usual temple stand 3 which is mounted upon the breast beam in the usual manner (not shown). The temple arm 4 is slidably mounted in the temple stand 3 and held in
15 extended position by the usual spring (not shown) and is provided with a temple head 5 having a downwardly extending heel 6 which lies in the path of the lay and is en-
gaged by it upon each beat-up of the lay.
20 The thread parting device may be of any usual construction. As illustrated herein it comprises a stationary blade 7 which is rigidly secured to the temple head and a reciprocating and oscillating movable cutter blade
25 8 which is slidably mounted in suitable ways in the head and is provided with a hook-shaped end 9 to engage, and upon reciprocation of the cutter to sever, the filling. The cutter blade 9 is provided with a downward-
30 ly extending heel 10 which lies in the path of the lay and is normally held in advance of the heel 6 of the temple by a spring 11 which is secured at its upper end to a suit-
35 able stud upon the temple arm 4 and at its lower end is wound about a stud 12 pro-
jecting from the heel 10 of the cutting blade 8. The parts above described may be and desirably are of a usual construction.
40 The mechanism for controlling the move-
ment of the thread parting device, or as illus-
trated herein the cutting blade, comprises a detent 13 having a hook-shaped end 14 which is adapted to engage the stud 12 upon the heel 10 of the cutting blade. The detent
45 13 desirably is formed in longitudinally ex-
tensible sections and is pivoted upon a stud 15 projecting laterally from the temple stand 3. As illustrated herein the section 16 of the detent which is pivoted upon the stud 15
50 is provided with a longitudinally extending groove 17 which receives a complementary rib 18 (see Fig. 5) upon the end section 13 of the detent, the sections of the detent be-
ing secured together in adjusted position by
55 a bolt 19. The detent is provided with a downwardly extending arm 20 adapted to engage and rest upon the breast beam of the loom and to limit the downward movement of the detent when it engages the stud 12 of the heel of the cutter.
60 While the weight of the detent may be sufficient to cause it to descend until the lug 20 is arrested by its engagement with the breast beam such depression desirably is
65 insured by providing a helical spring upon

the stud 15 with one end of the spring anchored in the temple stand and the other end anchored in the detent. This spring not only serves to depress the detent, but to hold the hooked end thereof positively in
70 engagement with the stud 12 during the normal operation of the loom.

The detent is provided with a laterally projecting stud 21 which extends across the path of an arm 22 which is fixedly secured
75 to the controller rod 2 by a set screw 23. When transfer is called for during the operation of the loom the controller rod 2 and its arm 22 are rotated in a counter-clockwise direction thereby raising the arm 22 causing it to engage the stud 21 on the
80 detent and upon further movement to raise the detent in such a manner that its hooked end is released from engagement with the
85 stud 12 which projects from the heel of the cutter as illustrated in Fig. 2. When the cutter is thus released it is projected by a spring into operative position and upon each beat-up the lay engages the heel of the
90 cutter and actuates it so that any filling end which projects from the selvage of the web of cloth will be severed by the co-operation of the hooked end 9 of the movable cutter and the stationary cutter 8.

It is desirable that the movable cutting blade shall be actuated a sufficient number of times after transfer takes place to insure the severance of the filling end which extends from the web of the cloth. The present invention relates to means for so controlling the detent that it will be held from operative position—that is to say the position in which it engages the stud 12—until the cutter has been actuated a predetermined number of times. The mechanism for accom-
100 plishing this purpose comprises a timing device which is carried by the temple stand and is bodily raised by the detent when the cutter is released. The timing mechanism is provided with means operable when thus raised to lock the detent in inoperative position and when the timing device is restored to its normal position the detent is withheld from engagement with the thread parting device until the timing device has been inter-
105 mittently actuated a predetermined number of times by or through the movement of the lay.

The timing device comprises a rotatable toothed disk or ratchet 24 which is ro-
110 tatably mounted upon a stud 25 projecting from the end of an arm 26 which is mounted upon a stud 27 extending laterally from the temple. The arm 26 has at its pivoted end an extension 28 which underlies a stop, preferably a lug 29, extending from the temple stand 3. The rotating timing device or ratchet 24 is provided with retaining means positioned to engage the detent 13
115 at predetermined times. In the preferred
120

embodiment of the invention illustrated herein the rotary timing device or ratchet is provided with a face cam in the form of a cam slot having a section 30 preferably substantially concentric with the axis of the timing device and an open end 31 desirably of somewhat larger diameter than the concentric portion of the cam slot. The detent 13 is provided with a laterally extending preferably cylindrical stud 32 which is located within the open end of the cam slot when the detent is in position to engage the stud 12 upon the heel of the movable cutting blade and is retained within the concentric portion of the cam slot and thereby locked in inoperative position during such period as the cutting blade remains in operative position.

The timing device or ratchet 24 is spring actuated in one direction. As illustrated herein the stud 25 has secured to it a cap 33 which houses a helical spring 34 which encircles the stud 25, one end of the spring being secured to the cap 33 and its opposite end to the rotatable timing device. The helical spring 34 acts to rotate the timing device in a counter-clockwise direction as viewed in the drawings. The rotatable timing device is provided with a laterally extending stud 35 which engages the arm 26 and limits the counter-clockwise movement of the stud when the stud 32 of the detent is located at or near the closed end of the cam slot as illustrated in Figs. 1 and 3. The rotatable timing device or ratchet 24 is provided with peripheral teeth 36 which may extend continuously around the ratchet disk, or as illustrated herein may be in the form of two sets 36 and 37, one set being adapted to be engaged by an actuating mechanism and the other by a suitable locking dog. The ratchet disk or timing device is rotated by a pawl 38 which is mounted upon the stud 12 which extends laterally from the heel 10 of the movable cutting blade. The pawl which is illustrated in detail in Fig. 6 comprises a relatively heavy V-shaped tooth having a cylindrical portion 39 which is rotatably mounted upon the stud 12 and is provided with a slot 40 which receives a pin 41 mounted in the stud 12. The pin 41 serves to limit the movement of the pawl. The pawl 38 is normally held in engagement with the ratchet by a helical spring 42 which encircles the stud 12 and has one end anchored in the pawl and its other end anchored in a cap 43 which is adjustably secured to the end of the stud 12. It is obvious that the reciprocation of the movable cutter when its heel is engaged by the lay will cause the pawl 38 to engage the teeth 36 of the rotatable timing device or ratchet and rotate the same in a clockwise direction.

Retrograde movement of the ratchet may

be prevented in any suitable manner. As illustrated herein it is prevented by a locking dog 44 which is pivotally mounted upon a stud 45 projecting laterally from the arm 26 which carries the rotatable timing device. The dog 44 is held in engagement with the teeth 37 of the ratchet by a helical spring 46 which surrounds the stud 45 and at one end engages the hub of the pawl and at its other end a cap 47 which is adjustably secured to the end of the stud 45.

In order to release the timing device and thereby permit it to rotate under the influence of its spring 34 means are provided for disengaging the pawl 44 from the ratchet when the detent is raised out of operative position. This is accomplished in the present embodiment of the invention by a lever 48 which is pivotally mounted at one end upon a stud 49 projecting from the temple stand and is provided at its other end with a lateral extension 50 which underlies the locking dog 44. The detent 13 is provided with a laterally extending stud 51 which underlies the lever 48 preferably about midway of its length and when the detent 13 is raised engages the lever 48 and rocks it about its pivot thus raising the end which underlies the pawl 44 and thereby raises the pawl 44 out of engagement with the teeth 37 of the ratchet of the timing device.

In the normal operation of the loom the hooked end 14 of the detent normally engages the stud 12 and holds the movable cutting blade out of operative position against the operation of the spring 11 which normally tends to project the cutter into operative position (see Fig. 2). When the detent is thus in operative—cutter-engaging—position the stud 32 of the detent is located in the open end or mouth 31 of the cam slot 30 as shown in Figs. 2 and 6. Upon call for transfer the controller rod 2 is rotated by the changing mechanism of the loom in a counter-clockwise direction thus raising the offset end of its arm 22 into engagement with the stud 21 upon the detent 13, thereby raising the detent out of engagement with the stud 12. During the continued upward movement of the controller arm 22 the stud 32 upon the detent 13 is raised into engagement with the inner wall of the concentric portion of the cam slot 30 and upon further upward movement of the detent raises the timing device—as permitted by its pivotally mounted supporting arm—thereby raising the teeth of the ratchet from engagement with the pawl 38. When the pawl is thus disengaged the rotation produced by its spring 42 is limited by the engagement of the pin 41 with the end of the slot in which it is located. As the detent 13 is raised by the controller arm its stud 51 engages the lever 48 and swings it about its pivot 49 thereby raising its offset free end into en-

gagement with the locking pawl 44, and upon further movement detaches the dog 44 from engagement with the teeth 37 of the ratchet of the timing device. The ratchet 5 of the timing device, thereby being freed of its engagement with the actuating pawl and locking dog, is rotated by its spring 34 in a counterclockwise direction until arrested by the engagement of its stud 35 with the supporting arm 26. During such rotation the concentric portion of the cam slot passes over the stud 32 until the stud is positioned adjacent to the closed end of the cam slot as illustrated in Figs. 1 and 3. After the 10 rotative movement of the controller rod 2 has thus initiated the action of the transferring mechanism of the loom the controller rod is rotated in a clockwise direction thus depressing the arm 22 and permitting the detent 15 to descend toward its operative position. The descent of the detent, however, is limited by the engagement of the extension 28 of the arm which supports the timing device with the lug 29 upon the temple stand so 20 that the parts are arrested immediately after transfer in the position illustrated in Figs. 1 and 3 with the closed end of the cam slot in substantially horizontal position and supporting the detent in the position illustrated in Figs. 1 and 2 out of the path of 25 movement of the stud 12 on the heel of the cutter blade. When in this position the teeth 36 of the ratchet are positioned in the path of the pawl 38 upon the stud 12 which projects from the heel of the movable cutter blade 10 which, it will be remembered, at this time, has been released and is projected to its operative position (as illustrated in Figs. 1 and 3) by its spring 11. 30 The downward movement of the detent permits the descent of the lever 48 which holds up the locking dog 44 and restores the locking dog to engagement with the teeth 37 of the ratchet. Immediately after transfer 35 therefore the heel 10 of the movable cutting blade is positioned in the path of the lay and the cutter is actuated upon each beat-up of the lay. As the cutting blade is thus reciprocated the pawl 38 engages successive 40 teeth 36 of the ratchet of the timing device upon successive beat-up movements thus rotating the timing device. Retrograde movement of the timing device is prevented by the engagement of the locking dog 44 with the successive teeth 37 of the ratchet, as the timing device is intermittently rotated by the reciprocating pawl 38. 45

The ratchet may be provided with any desirable number of teeth 36 corresponding to the number of beat-ups desired to insure severance of the filling end which extends from the selvage of the web after transfer. This intermittent rotation of the timing device or ratchet 24 in a clockwise direction 50 gradually moves the concentric portion of

the cam to the position in which its open end or mouth 31 is presented downwardly thereby releasing the stud 32 of the detent 13 and permitting the end of the detent to drop into the path of the stud 12 of the heel of the cutter blade. The hooked portion 14 of the detent thereupon engages the stud either as the detent drops or is caused to engage the stud upon the next beat-up of the lay as the stud 12 will engage the rounded end of the detent upon the next beat-up and raise the detent so that it will drop over the stud at the end of such beat-up. Thus the detent is again caused to engage the stud 12 of the movable cutter blade 55 and retain the cutter blade in inoperative position until said detent is again released upon the next call for transfer. The longitudinal adjustability of the detent permits the detent to be accurately positioned with respect to the field of travel of the stud upon the heel of the movable cutter blade and also facilitates the manufacture and proper assembly of the parts as will be readily recognized by those skilled in the art. 60

While the mechanism is illustrated herein as comprising a detent adapted to engage a stud upon the heel of a reciprocating and rocking cutting blade, it will be understood that the mechanism may be adapted to engage and withhold from operative position any other form of thread parting device to which it is adaptable. By reason of the construction above described the thread parting device is held in inoperative position during the normal weaving operation of the loom and is released upon call for transfer and thereafter actuated such predetermined number of times as will insure the severance of the filling end before being again locked in inoperative position. 65

The mechanism herein described for controlling the intermittent operation of the thread parting device is readily adaptable to usual types of looms and is of a rigid construction which will not be easily broken or damaged by the rough usage to which it is submitted during the operation of the loom. 70

It will be understood that the embodiment of the invention disclosed herein is of an illustrative character and is not restrictive and that various changes in form, construction and arrangement of parts may be made within the spirit and scope of the following claims. 75

Having thus described the invention, what is claimed as new, and desired to be secured by Letters Patent, is:

1. In a loom comprising automatic filling replenishing mechanism, a temple stand, a temple having a movable thread parting device operable by or through the movement of the lay, resilient means tending to hold said parting device in operative position, a 80

detent mounted on said temple stand normally positioned to engage said parting device upon the beat-up of the lay and thereafter to retain said parting device in inoperative position, means operable by the changing mechanism of the loom upon call for transfer to release said detent from engagement with said parting device, a timing device bodily movable with said detent having means to engage said detent and withhold it from engagement with said parting device and means operable by or through a predetermined number of movements of the lay following call for transfer to cause said timing device to restore said detent to engagement with said parting device.

2. In a loom comprising automatic filling replenishing mechanism, a temple stand, a temple having a movable thread parting device operable by or through the movement of the lay, resilient means tending to hold said parting device in operative position, a detent mounted on said temple stand normally positioned to engage said parting device upon the beat-up of the lay and thereafter to retain said parting device in inoperative position, means operable by the changing mechanism of the loom upon call for transfer for releasing said detent from engagement with said parting device, a spring actuated rotatable timing device movable with said detent having means for withholding said detent from engagement with said parting device and means operable by a predetermined number of movements of the lay following transfer for rotating said timing device in opposition to its spring to restore said detent to engagement with said parting device.

3. In a loom comprising automatic filling replenishing mechanism, a temple stand, a temple having a movable thread parting device operable by or through the movement of the lay, resilient means tending to hold said parting device in operative position, a detent mounted on said temple stand normally positioned to engage said parting device upon the beat-up of the lay and thereafter to retain said parting device in inoperative position, a timing device comprising a rotatable ratchet wheel having a locking device to engage said detent, a pawl on said movable parting device positioned to engage said ratchet upon the beat-up of the lay and rotate said ratchet intermittently in one direction, a spring tending to rotate said ratchet wheel in the reverse direction and means operable by the changing mechanism of the loom upon call for transfer to release said detent from engagement with said parting device and simultaneously to release said ratchet wheel whereby it will be rotated by its spring and its locking device caused to engage said detent and lock it in inoperative position until released by the intermittent

rotation of the timing device in the opposite direction.

4. In a loom comprising automatic filling replenishing mechanism, a temple stand, a temple having a movable thread parting device operable by or through the movement of the lay, resilient means tending to hold said parting device in operative position, a detent mounted on said temple stand normally positioned to engage said parting device upon the beat-up of the lay and thereafter to retain said parting device in inoperative position, a timing device comprising a rotatable ratchet wheel having an open-ended cam slot to receive a pin on said detent, a pawl on said movable parting device positioned to engage said ratchet wheel upon the beat-up of the lay and rotate it intermittently in one direction, a spring tending to rotate said ratchet wheel in the reverse direction and means operable by the changing mechanism of the loom, upon call for transfer, to raise said detent from engagement with said parting device and simultaneously to release said ratchet wheel, whereby it will be rotated by its spring in said reverse direction and its cam caused to lock the detent in inoperative position until released by a predetermined number of said intermittent rotative movements of the ratchet.

5. In a loom comprising automatic filling replenishing mechanism, a temple stand, a temple having a movable thread parting device operable by or through the movement of the lay, resilient means tending to hold said parting device in operative position, a detent mounted on said temple stand normally positioned to engage said parting device upon the beat-up of the lay and thereafter to retain said parting device in inoperative position, an arm pivotally supported upon the temple stand having mounted thereon a rotatable timing device provided with locking means to engage said detent and a ratchet wheel intermittently rotatable in one direction by the movement of the parting device, means operable by the changing mechanism of the loom temporarily to raise said detent from engagement with said parting device and simultaneously to release said timing device and a spring acting to rotate said timing device in a reverse direction, when thus released, whereby its locking means will retain said detent out of engagement with said parting device until restored by a predetermined number of intermittent rotative movements of said timing device.

6. In a loom comprising automatic filling replenishing mechanism, a temple stand, a temple having a movable thread parting device operable by or through the movement of the lay, resilient means tending to hold said parting device in operative position, a detent mounted on said temple stand nor-

- mainly positioned to engage said parting device upon the beat-up of the lay and thereafter to retain said parting device in inoperative position, an arm pivotally supported upon the temple stand having mounted thereon a rotatable timing device comprising a ratchet wheel having locking means to engage said detent, a dog pivotally mounted on said arm engaging said ratchet wheel,
- 5 10 a pawl on said parting device adapted upon reciprocation of said parting device intermittently to rotate said ratchet wheel in one direction, means operable by the changing mechanism of the loom temporarily to raise
- 15 20 said detent out of engagement with said parting device and simultaneously to raise said ratchet wheel out of the path of the pawl on the parting device, means operable by the movement of said detent to release
- 25 30 said dog from said ratchet and a spring acting to rotate the timing device when released in the reverse direction and thereby to cause its locking device to retain the detent in inoperative position until restored by a predetermined number of intermittent rotative movements of said timing device.
7. In a loom comprising automatic filling replenishing mechanism, a temple stand, a temple having a thread cutter provided with a reciprocable blade having a heel located in the path of the lay, a stud projecting laterally from said heel, a detent pivotally mounted upon said temple stand having means to engage said stud, an arm pivotally mounted upon said stand having at its free end a timing device comprising a ratchet having an open-ended cam slot to engage a stud upon said detent, a pawl mounted upon said cutter adapted to engage said ratchet and upon reciprocation of the lay to rotate said ratchet in one direction, a spring acting to rotate said ratchet in the opposite direction, a dog pivotally mounted upon the arm which supports the timing device engaging said ratchet, a lever pivotally mounted upon said stand having its free end underlying said dog and engaging a stud upon said detent and an arm connected to the controller shaft
- 35 40 45 50 55 60 65 70 75 80 85 90 of the loom adapted to engage a stud upon said detent and, upon call for transfer, to raise said detent from engagement with the stud upon said cutter thereby releasing the cutter and through the stud on said detent raising the timing device and simultaneously actuating the lever to release said dog, whereby the spring of the timing device will rotate the timing device in the reverse direction and cause the cam slot in the timing device to lock the detent in inoperative position and to retain said detent in inoperative position after restoration of the controller arm to normal position until said ratchet is given a predetermined number of intermittent rotative movements by the reciprocation of said cutter.
8. In a loom comprising automatic filling replenishing mechanism, a temple stand, a temple having a movable thread parting device operable by or through the movement of the lay and resilient means tending to hold said parting device in operative position; a sectional longitudinally adjustable detent pivotally mounted on said temple stand to engage said parting device upon a beat-up of the lay and thereafter to retain it in inoperative position, means operable by the changing mechanism of the loom for releasing said detent from said parting device, a spring actuated rotatable timing device, means operable by the movement of said detent when released from said parting device to permit said timing device to be rotated, by its spring, in one direction, and co-operating locking means on said timing device and detent respectively operable by such rotation to engage and retain said detent out of engagement with said parting device and means operable by the movement of said parting device to rotate said timing device intermittently in the reverse direction whereby a predetermined number of such movements will unlock said detent and permit it to engage said parting device.
- In testimony whereof, I have signed my name to this specification.
- ALONZO E. RHOADES.
